UNITED STATES PATENT OFFICE.

MAX E. SCHECK, OF CHICAGO, ILLINOIS.

DESIGN FOR A CUT-GLASS BOWL.

No. 38,923.

Specification for Design.

Patented Dec. 3, 1907.

Application filed October 14, 1907. Serial No. 397,456. Term of patent 3½ years.

To all whom it may concern:

Be it known that I, MAX E. SCHECK, a citizen of the United States, residing at Chicago, in the county of Cook and State of Illinois, have invented a new, original, and ornamental Design for a Cut-Glass Bowl, of which the following is a specification, reference being had to the accompanying drawing, forming a part thereof.

The design is illustrated in the three figures of the drawing, Figures 1 and 2 being

side views of the bowl showing different portions of the design and Fig. 3 being a bottom plan view of the bowl.

I claim:

The ornamental design for a cut glass bowl, as shown.

MAX E. SCHECK.
